UNITED STATES PATENT OFFICE.

CHARLES W. POST, OF FORT WORTH, TEXAS, ASSIGNOR TO THE SCIENTIFIC SUSPENDER COMPANY, LIMITED, OF BATTLE CREEK, MICHIGAN.

SUSPENDERS.

SPECIFICATION forming part of Letters Patent No. 508,048, dated November 7, 1893.

Application filed September 8, 1891, Serial No. 405,124. (No model.)

To all whom it may concern:

Be it known that I, CHARLES W. POST, a citizen of the United States, residing at Fort Worth, in the county of Tarrant and State of Texas, have invented certain new and useful Improvements in Suspenders, of which the following, taken in connection with the accompanying drawings, is a full, clear, and exact specification.

10 The object of my invention is to reduce to a minimum the number of straps or cords and buckles required in the construction of suspenders, and also the number of buttons necessary for their attachment to the garment, 15 and to provide suspenders which may be more readily and conveniently attached, than heretofore, and will permit of free movement of the body without discomfort to the wearer.

With these objects in view my invention 20 consists primarily in connecting the ends of the front and back straps of the suspenders to the button-hole cord between the two button-holes of the same pair of button-holes, that is to say, between two adjacent button-holes, 25 in such a manner that there shall be no button-hole between the ends of the said strap, or between such ends and the button-holes of the pair between which such straps are connected to the cord; thus connecting the ends of the 30 straps by that part of the button-hole cord which carries at its ends, button holes for attachment to a single pair of suspender buttons.

My invention also consists in certain other 35 features of novelty hereinafter fully described in connection with the drawings and particularly pointed out in the claims.

In said drawings Figure 1 is a perspective view from the side, showing my improved suspenders in position on the wearer. Fig. 2 is a 40 rear view of the same, and Fig. 3 is an enlarged perspective view of the complete device.

In constructing a pair of suspenders according to my invention, I employ but two shoulder straps, A, A', which are crossed in the back and held in place, preferably by two loops, B, C, one on each of the said straps. These loops are elongated so as to permit the straps to be crossed at a point convenient and suitable to the wearer, the loop, B, being 45 secured to one strap, A, and crossing the strap A', while the loop C is secured to the strap A'

and crosses the loop B, thus bringing both loops on the inside and yet avoiding the formation of a bunch or lump which would be uncomfortable to the wearer. The forward 55 ends of the straps A, A' form the front straps, a, for the right and left sides respectively, while their rear ends constitute the right and left back straps, a'. Each strap, A, A', is provided at one end with a slide, or other well 60 known and suitable adjusting device, D, and at both ends with pulleys, or other suitable anti-friction devices, E, E, which retain and support the button-hole cords, F, F, both pulleys on each side being arranged between the 65 two button-holes of the same pair, as clearly shown, whereby both pulleys will be free to go and come throughout the whole length of the cord between such button-holes.

With suspenders constructed according to 70 my invention, it is only necessary to employ four suspender buttons in all, which are located on the waist band as shown in the drawings, two on each side of the pantaloons, the forward ones being about an inch forward of the side seam, α , and the rear ones being about four inches to the rear of such seam, thus bringing the buttons on each side of the pantaloons about five inches apart. When in use the pulleys, E, E, assume the position 75 shown in Fig. 1, in which position they hold the ends of the button-hole cords apart and effectually support the pantaloons both at front and back without producing the objectionable dragging sensation so common with 80 contrivances heretofore employed. It will be understood that this fault is obviated in my invention, by reason of the fact that when the body is bent forward in the act of stooping or otherwise, the angle at which the button-hole 85 cord is held, changes, and both pulleys shift forward on the cord as shown in dotted lines, Fig. 1, transferring the center of suspension from the point G, in the rear of the side seam, to the point O, thus permitting the waistband 90 to remain in substantially its original or normal position.

Ordinary suspenders are attached in front at H, and in the rear at I, the pivot of the body being at L. In the act of stooping or 95 sitting, the body swings forward on the pivot L, and the back describes an arc, say from I

to K, and therefore the pantaloons' band must either be drawn upward from I to K, or the material of the pantaloons or suspenders must stretch that distance. In either case great straining of the parts is produced. With my invention, even in case the center of suspension did not shift as described, a very slight stretch of its material would be sufficient to compensate for the movement of the button from M to N, without straining; but in view of the fact that the point of suspension invariably moves from G to O, any upward pull at M is practically obviated.

I am well aware that it is not broadly new 15 to connect the front and back straps of the suspenders to a button-hole cord passing from the front to the rear suspender buttons, but such is not a single button-hole cord in the sense in which the term "single" is herein employed, that is to say, not to that portion 20 of the cord which extends between two adjacent button-holes.

Having described my invention, what I claim, and desire to secure by Letters Patent,

25 is—

1. A pair of suspenders consisting of two shoulder straps each provided at both ends with a pulley, and two button hole cords having a button hole in each end thereof only,

one of said cords working over the pulleys 30 and connecting one end of each strap and the other cord working over the other pulleys and connecting the other ends of said straps, substantially as described.

2. A pair of suspenders consisting of two 35 shoulder straps each provided at both ends with a pulley, and a single integral continuous button - hole cord of uniform thickness throughout its length, having a button-hole in each of its extremities only, arranged at 40 each end of each of said straps, each of said cords passing through one of the pulleys on each of the straps, so that both pulleys at each end of the straps will be located between the two button-holes of the same pair 45 and will be free to slide on said cord from one button-hole to the other, whereby the suspenders may be attached to the pantaloons slightly forward of each side-seam and also in the rear of each side-seam about four times 50 as far therefrom as the distance between the aforesaid points of attachment and the side-seam, substantially as set forth.
